US0D1075217S

(12) **United States Design Patent** (10) Patent No.: **US D1,075,217 S**
(45) Date of Patent: ** May 20, 2025

(54) **GARMENT WITH BODY SHAPE
ENHANCING APPARATUS**

(71) Applicant: **Armani Ibrahim**, Staten Island, NY
(US)

(72) Inventor: **Armani Ibrahim**, Staten Island, NY
(US)

(73) Assignee: **Armani Ibrahim**, Staten Island, NY
(US)

(**) Term: **15 Years**

(21) Appl. No.: **29/890,725**

(22) Filed: **Apr. 26, 2023**

(56)

(57) **CLAIM**

The ornamental design for the garment with body shape enhancing apparatus as shown and described.

DESCRIPTION

(63) Continuation-in-part of application No. 18/132,901, filed on Apr. 10, 2023, now Pat. No. 12,089,661, and a continuation-in-part of application No. 17/562,542, filed on Dec. 27, 2021, now Pat. No. 11,647,797, and a continuation-in-part of application No. 29/816,996, filed on Nov. 27, 2021, now Pat. No. Des. 992,859, (Continued)

FIG. 1 is a top, left, and rear perspective view of a garment with body shape enhancing apparatus in accordance with the present invention;

FIG. 2 is a rear elevational view of the garment with body shape enhancing apparatus;

FIG. 3 is a front elevational view of the garment with body shape enhancing apparatus;

FIG. 4 is a right side elevational view of the garment with body shape enhancing apparatus, the left side elevational view being a mirror image of the right side view;

FIG. 5 is a top plan view of the garment with body shape enhancing apparatus;

FIG. 6 is a bottom plan view of the garment with body shape enhancing apparatus; and,

FIG. 7 is a front portion of the garment with body shape enhancing apparatus in full lines with person and environment shown in broken lines.

The broken lines in FIGS. 1–6 depict portions of the article that form no part of the claim. The broken lines showing of the figure in FIG. 7 depicts environmental subject matter and forms no part of the claim.

1 Claim, 7 Drawing Sheets

Related U.S. Application Data

and a continuation-in-part of application No. 29/761, 650, filed on Dec. 10, 2020, now Pat. No. Des. 942,119.
